UNITED STATES PATENT OFFICE.

VIRGIL W. BLANCHARD, OF NEW YORK, N. Y., ASSIGNOR TO JOSEPH A. DAVIS, OF SAME PLACE.

GRATE FOR FURNACES.

SPECIFICATION forming part of Letters Patent No. 413,898, dated October 29, 1889.

Application filed April 4, 1889. Serial No. 305,968. (No model.)

To all whom it may concern:

Be it known that I, VIRGIL W. BLANCHARD, of New York, in the county of New York and State of New York, have invented certain 5 new and useful Improvements in Grates for Furnaces; and I do hereby declare that the following is a full, clear, and exact description thereof, reference being had to the accompanying drawings, and to the letters of 10 reference marked thereon, which form part of this specification, in which—

Figure 1 is a perspective sectional view of a portion of my improved grate and portions of the bearers or frame therefor. Fig. 2 is 15 an elevation in detail, and partly in section, of a portion of the grate. Fig. 3 is the perspective view of one of the sections of the rocking bars. Fig. 4 shows one of the connecting-links for the lower pivotal rods of said bars. 20 This invention relates to furnace-grates; and it consists in the combination of oscillating or rocking sectional crushing-bars with stationary bars so constructed that any clinkers or vitreous or earthy substances that the 25 fuel may contain can be crushed. At the same time provision is made for supplying air from the ash-pit to the fuel in regulated quantities as circumstances may require.

The following description, when taken in 30 connection with the annexed drawings, will enable others skilled in the art to fully understand the construction and operation of my improved grate.

The rocking bars of the grate are composed 35 of sections arranged in parallel rows between stationary bars B, which are suitably supported at their extremities upon or by the furnace-brick lining. The stationary bars B may constitute a rigid frame, within which 40 the bars A are allowed to be rocked. Each one of the sections of the movable bars A is constructed with an enlarged crushing-head A', preferably of the angular form shown in Figs. 1 and 3, in the sides of which head are 45 grooves a a. Below the head A' is an eye d, through which passes a fulcrum pivotal rod D, and below this eye d the section is contracted laterally and provided on one side with an oblong tenon b and on the opposite 50 side with a mortise b', of a corresponding shape and size to that shown in Fig. 2. The lower

or lever path of each section A is provided with ribs c c, below which is an eye d', for receiving a pivotal connecting-bar E. Each row of sections forming bars A are closely 55 fitted together, and are locked by the tenons and mortises above described. The curved grooves in the sides of adjoining sections A form passages a' for admitting air from the ash-pit in jets to the fuel on the grate. The 60 air is thus admitted through the bars, as well as between them, thereby insuring a more thorough and even distribution of the air and oxidation of the fuel.

Each row of sections A vibrates about a 65 fulcrum-rod D, and all of the rows of sections are connected together by links G, through which pass the pivotal rods E, so that all of the said bars A can be rocked simultaneously by means of a rod C, which in practice will 70 be connected to an angular lever. (Not shown in the drawings.)

The stationary bars, which are arranged between the movable bars, are constructed with double beveled heads having grooves e 75 in them, and below these heads the bars are in cross-section bifurcated, as shown in Fig. 1, leaving inverted-V-shaped grooves B² longitudinally through them. These grooves B² trap air, which keeps the bars from melting 80 or sagging.

It will be observed that I have a grate by which clinkers can be easily crushed to powder, and that by means of the small passages a' air will be at all times supplied to the fuel 85 in jets sufficient to maintain combustion of the fuel.

Having described my invention, I claim—

1. The combination, in a grate, of stationary bars with intermediate rocking bars having 90 crushing-heads provided with a series of air-passages, for the purpose and substantially as described.

2. In a grate, the combination of stationary bars having double beveled heads, with a series of intermediate rocking bars having 95 double beveled heads formed with air-passages, whereby air is admitted through the bars, substantially as and for the purpose specified.

3. In a grate constructed with movable bars, the combination therewith of longitudinally-

- grooved stationary bars having double beveled and grooved heads and longitudinally grooved on their under surfaces, substantially as described.
- 5 4. The movable hammer-headed bars composed of sections locked together and provided with air-jet passages, as described, in combination with the stationary bars, as specified.
- 10 5. The combination, with a series of stationary bars, of a series of rocking bars parallel with and between the stationary bars, said rocking bars being composed of sections fitted together by tongue-and-socket joints and provided with coincident grooves forming air passages, substantially as described.
- 15 6. The combination of a series of stationary bars having double inclined and grooved upper edges with a series of rocking bars alternating with said stationary bars and having enlarged and perforated heads and depending shanks, and the uniting-links between said rocking bars for operating them simultaneously, substantially as set forth.
- 20 7. The combination, with the stationary bars, of intermediate rocking bars composed of sections fitted together upon a supporting-rod, and having enlarged heads channeled on their meeting edges, and depending shanks, the rods passing through said shanks, and the links connecting said rods for operating the rocking bars, substantially as specified.
- 25 8. The combination of the grate-bars having inclined upper edges and longitudinally channeled or grooved, with a series of rocking bars composed of similar sections having enlarged heads grooved on their meeting faces, and tongues and sockets for locking the adjoining sections together, and the links and rods for rocking said bars, substantially as described.
- 30 9. The herein-described grate, composed of a series of stationary bars having a longitudinal channel at bottom and their upper edges beveled and grooved, with a series of rocking bars composed of similar sections fitted on a suspending-rod, each section having an enlarged double beveled head channeled on its sides, and a tongue and socket on its depending portion or shank, and a laterally-perforated eye, and the rods passing through said eyes, the links connecting said rods, and the operating-rod for rocking the bars, all substantially as and for the purpose specified.
- 35 In testimony that I claim the foregoing as my own I affix my signature in presence of two witnesses.
